UNITED STATES PATENT OFFICE.

WILLIS L. HARROLD, OF MISHAWAKA, INDIANA.

BOTTLE CLOSURE.

Application filed May 10, 1928. Serial No. 108,201.

The invention relates to bottle closures, and has for its object to provide in combination with a bracket disposed at one side of a bottle neck and having hingedly connected 5 to the upper end thereof a closure for the bottle, a segmentally shaped member arching the side of the neck of the bottle and connected to the bracket in a manner whereby it may be adjusted upwardly or downwardly 10 according to the length of the neck of the bottle, and the configuration of the neck of the bottle.

A further object is to provide the bracket, which supports the cover, with spaced vertically disposed elongated slits, the portion between which slits is struck in, thereby forming adjacent gripping corners and a segmentally shaped spring member extending through the bracket horizontally between 20 the bracket and the struck out portion and forming gripping arms for gripping opposite sides of a bottle neck and detachably holding the bracket on the neck, said gripping corners gripping the segmentally 25 shaped spring member upon spreading of the opposite ends thereof thereby preventing circumferential displacement thereof when on a bottle neck.

With the above and other objects in view 30 the invention resides in the combination and arrangement of parts as hereinafter set forth, shown in the drawings, described and claimed, it being understood that changes in the precise embodiment of the invention may 35 be made within the scope of what is claimed without departing from the spirit of the invention.

In the drawing:

Figure 1 is a side elevation of the cap and support showing the same attached to the neck of a conventional form of bottle.

Figure 2 is a top plan view of the closure.

Figure 3 is a rear elevation of the bracket and gripping member.

Figure 4 is a horizontal sectional view taken on line 4—4 of Figure 3.

Referring to the drawing, the numeral 1 designates a conventional form of milk bottle, 2 the neck thereof, and 3 the bottle bead. 50 In milk bottles and bottles generally the necks thereof vary in length and configuration, consequently in providing a supporting bracket 4, which is attached to the neck by oppositely disposed spring gripping arms 5, 55 it is necessary and desirable to have means

whereby the supporting arms 5 can be adjusted upwardly or downwardly in a horizontal plane, and to accomplish this result the bracket 4 which is vertically disposed is provided with spaced vertically disposed 60 slits 6, the portion 7 of which between which slits is struck inwardly and the segmentally shaped spring member 8, which forms the gripping arms 5, extends through the bracket in a horizontal plane between the portion 7 65 thereof and the inner side of the bracket, and it will be seen the spring member 8 will be gripped by the adjacent gripping edges 9 of the inwardly struck portions 7, and the gripping edges 10 of the bracket 4, and the 70 said gripping will be positive as the spring member 8 is arcuately shaped and the adjacent surfaces of the bracket 4 and inwardly struck portion 7 are in parallel planes thereby allowing the entire gripping and holding 75 action to take place on the gripping corners 9 and 10, and at the same time as the inwardly struck portion 7 is relatively long in relation to the width of the segmentally shaped spring member 8, said spring member 80 80 may be easily adjusted upwardly or downwardly as desired according to the shape and configuration of the bottle neck 2, and the type of bottle on which the device is applied. It will be noted by flattening 85 out or straightening the spring member 8 it may be easily forced into position and properly adjusted, thereby reducing the cost of assembling to a minimum.

The upper end of the bracket 4 is provided with a vertically disposed offset portion 11 to one side of the bottle bead 3, and hingedly connected at 12 to said bracket portion 11 is a closure 13. The rear side of the closure 13 is provided with a downwardly 95 extending finger engaging member 14 adapted to be engaged by the finger of the operator for opening the closure 13 when pouring the contents from the bottom 1, and interposed between said finger engaging portion 14 and the upwardly extending portion 11 of the bracket 4 is a bowed spring 15 which normally exerts an outward pressure on the finger engaging member 14 and maintains the closure 13 in closed position. 100 Bowed spring may be brazed or otherwise secured at 16 to the bracket 4.

From the above it will be seen that means is provided for attaching and holding a hinged bottle closure on the neck of a bottle 110

by means of a segmentally shaped spring member adapted to grip opposite sides of the neck, and which spring member may be adjusted to various horizontal planes in relation to the closure, and said spring member is gripped by adjacent oppositely disposed gripping edges carried by the bracket.

10 The invention having been set forth what is claimed as new and useful is:—

1. The combination with a bottle closure comprising a hinged cap cooperating with a bottle neck and a bracket to which said cap is hingedly connected, said bracket being disposed to one side of the neck of a bottle, of a segmentally shaped horizontally disposed spring member arching the neck of the bottle and gripping opposite sides thereof, said 15 segmentally shaped spring member being vertically adjustable to various horizontal planes and held by the bracket.

2. The combination with a bottle neck, a bracket disposed to one side of said bottle

neck, a closure hingedly connected to said bracket, of an arcuately shaped spring member carried by the bracket and having its ends engaging opposite sides of the bottle neck, said bracket being provided with a vertically elongated struck in portion, said arcuately shaped member being disposed between the struck in portion and the adjacent side of the bracket, said struck in portion and bracket having adjacent gripping edges cooperating with opposite sides of the 20 arcuate spring member and forming means whereby said arcuate spring member is held against circumferential displacement and in various adjusted positions in horizontal plane.

3. The combination with a jar closure cap supporting bracket, of a neck engaging spring member carried by said bracket, said neck engaging member being adjustable to various planes in a horizontal position.

In testimony whereof I affix my signature.

WILLIS L. HARROLD.
